Application March 25, 1947, Serial No. 737,073
In Germany September 30, 1944

Section 1, Public Law 690, August 8, 1946
Patent expires September 30, 1964

12 Claims. (Cl. 12—9)

1

This invention relates to a driving arrangement for pulling over machines, toe tacking machines and the like shoemaking machines, in which the upper part of the shoe is stretched over the last by means of a system of stretching nippers which alternately close and open, perform pulling and lateral motions, in some cases a rotary motion about their own axis and also the corresponding return motions, and has for its object an improvement in the drive of the nippers. According to the invention this is effected by the provision of a hydraulic drive with differential pistons and a spring-loaded by-pass valve between the latter, which parts co-operate in such a manner that, during the stretching motion of the nippers, the tractive force of the nippers increases in the ratio of the increasing resistance of the upper up to a definite maximum value, the closing force of the nipper jaws increasing simultaneously to a corresponding extent.

The stretching nippers of pulling over and toe tacking machines have essentially two fundamental operative functions to perform, namely the clamping of the marginal portion of the upper between the nipper jaws and the stretching of the upper through the pull of the nippers. To these fundamental functions of the nippers must be added lateral evading motions which are necessary, when the nipper jaws are opened, in order to free the place being operated on for fixing means, and of course all return motions after the completion of the operation. In the case of those nippers which are operative in the ball part of the shoe, that is, the so-called ball nippers, a rotary motion of the nippers about their longitudinal axis as well is desirable, in order to ensure a correct adaptation and stretching out of the upper in the instep arch of the last.

The correct tacking of a shoe upper, that is, its fixing on the inner sole of the shoe, is mainly dependent on the correct stretching of the upper on the last and the pulling over round the edge of the last and the inner sole, which operations are regulated by the grip and pull of the stretching nippers. The material of the shoe upper, that is usually leather, has the peculiarity, that at first it offers to the tensioning force a relatively low resistance which gradually increases as the pulling operation proceeds, until it reaches a definite extreme value, the exceeding of which would result in the upper part tearing. This extreme value must therefore never be exceeded, when the upper part is being stretched over the last, with the further object of insuring that the shoe will retain the requisite elasticity, even after the tacking on of the upper part.

2

With the arrangement according to the present invention it is intended first of all to solve the problem, for the correct stretching of an upper part corresponding to the nature of the leather, to follow a procedure which has proved to be the best in the stretching and tacking on operation by hand after years of experience, as the worker first of all, after gripping the marginal portion of the upper, applies a gentle pull which he increases in accordance with the increasing resistance of the upper, at the same time increasing the force required for holding the upper part in the nippers. An advantageous feature of the arrangement according to the invention resides in the simplicity of the construction, in the possibility of controlling individual groups of nippers by themselves and not least in the circumstance, that the upper can in every working phase of the machine be liberated from the nippers by a single movement of a lever.

Owing to the circumstance, that with the purely hydraulic drive according to the invention the closing force of the nipper jaws is hydraulically controlled together with the pull of the nippers, a considerable simplification of the entire device results, although each nipper has its individual drive and thus represents an independent working element, of which some, through being connected to common control valves, form the usual working groups, such as toe nipper, side nippers and perhaps ball nippers. The individual working nippers are supported by working cylinders capable of being fixed in any position on the machine frame, in which cylinders the pistons supporting the fixed nipper jaw move, whilst the movable nipper jaw is mounted on a rod which at one end is also formed as a piston and is guided within the piston casing of the fixed nipper jaw. This arrangement provides differential pistons with an intermediate space which is in communication with the cylinder space of the working cylinder by way of a spring-loaded by-pass valve. Through the inflow of the pressure fluid the closing of the nipper jaws is thus first of all brought about by a relative displacement of the two pistons with respect to one another and finally, through the joint movement of the two pistons in the working cylinder, the pulling motion is produced, in which during the equalization of pressure in the spaces between the differential pistons and the working cylinder the said increase of the pulling force and the nipper closing force takes place. An axial rotary motion of the nippers, if required, is derived from the sliding motion of the same in the working cylinder. The gripping of the marginal portion

of the upper by the nipper jaws and the tensioning of the upper through the pull of the nipper is effected by the worker through controlling the appropriate valves by means of a knee-actuated lever, whereby he can control each group of nippers independently not only in regard to the working position, but also for the purpose of returning it into the initial position, which is of great advantage, if the marginal portion of the upper should by chance have been incorrectly gripped and tensioned by only one group of nippers. Only after the upper has been correctly stretched over the last are the valves controlling the nippers changed over to the cam shaft of the machine, which can then automatically carry out the further work, such as the forming and tacking on of the upper.

Further advantages and features of the present invention will be gathered from the following description with reference to a constructional example illustrated in the accompanying drawings, in which:

Figure 1 shows a diagrammatic representation of the whole driving arrangement according to the invention;

Figure 2 a longitudinal section through the stretching nippers in the initial position;

Figure 3 a detail of the working cylinder of the nippers in section (in the upper part of the figure the parts are in a position, in which the nipper jaws are closed, but the nippers themselves are not yet exerting any pulling force, whilst the lower part of the figure shows the position of the parts, when the nippers are exerting the pull);

Figure 4 a view of a control slide valve in part section with the piston in the initial position;

Figure 5 a diagrammatic representation of one of the control chambers with the piston in a middle position;

Figure 6 the same control chamber as Figure 5 with the piston in the extreme left-hand position;

Figure 7 a diagrammatic representation of the idle running slide valve in cross-section, and

Figure 8 a detail of the means for driving the piston of the idle running slide valve.

The arrangement for stretching the toe part of the shoe upper over the last consists in the tacking machine constructed according to the invention of the usual system of stretching nipper, of which the nippers 1 (Figure 1) represent the toe nipper, the nippers 2, 2' the side nippers and 3, 3' the nippers for applying the pull in the ball region, the ball nippers. The number of pairs of nippers could, of course, be increased according to requirement. The individual nipper arrangements differ from one another only in the shape of the jaws and, as regards the ball nippers 3, 3' also in this, that the latter are provided with a device which enables these nippers to turn about their longitudinal axis, which is not necessary in the case of the toe and side nippers.

The drive of all the nippers is fully hydraulic. The pressure fluid, for instance, oil, is conveyed by a pump 4 driven by the electric motor 5 from a container 6 through the pipe 7 by way of a filter 8. The container 6 is suitably mounted in the lower part of the machine. The pump 4 conveys the oil through a pipe 9 by way of a so-called idle running slide valve 10 and through the outflow pipe 11 of this slide valve into the pressure pipe line 12, to which all the control slide valves of the stretching nippers are connected. At the end of the pressure pipe line 12

there is a safety pressure valve 13 of known construction, by means of the small hand wheel 14 of which the maximum oil pressure in the pipe 12 can be set. The safety valve 13 allows superfluous oil to flow out of the pressure pipe line through a pipe 15 back into the container 6. The pressure in the pipe 12 is checked by the pressure gauge 16.

The piston 21 (Figure 7) of the idle running slide valve 10 is slidable in the valve chamber 17 which can be brought into communication through a connection 9 with the pump 4, through the outflow pipe 11 with the pressure pipe 12 and through an outflow pipe 13 with the container 6. The valve chamber 17 is provided at the place between the orifice of the connection 9 and the pipe 11 with a recess 19 which is in the same position as a corresponding recess 20 in the piston 21. This piston 21 has at its left-hand end a conical extension 22 provided with ribs 23, against which bears a spring 24 which seeks to force the piston 21 out of the chamber 17. The right-hand end of the piston 21 carries a pin 25 projecting from both sides of the piston body 21 (cf. Figure 8) and a roller 26. The piston 21 can be actuated either by a lever operated by the knee of the worker or automatically by a cam disc by the machine, as will be described later, and has as its main function to enable the pump 4 to run idle, when, the individual devices being inoperative, no pressure oil is required in the pipe 12. The pressure fluid present in the pressure pipe 12 is prevented from flowing back by a non-return valve 152 loaded by a spring 153.

As already stated, the individual nippers are almost exactly alike in construction and each group of nippers has a common slide valve. It should therefore suffice to describe hereinafter the arrangement of a single group of nippers with the slide valve belonging to it.

Each nipper forms an independent mechanical unit which is housed in the working cylinder 27 (Figure 2) which is in fixed communication with a tubular extension 28. The tubular extension 28 is clamped in an adjustable socket 29, by means of which the nipper can be fixed to holders of a known kind (not shown), which latter can be controlled in a known manner by hand levers, such that each nipper can be displaced with respect to the work, as is, for instance, necessary, when changing over from one kind of shoe or size of shoe to another, or as may seem necessary when stretching the upper over the last. Thus, the toe nipper 1 is adjustable in the longitudinal axis of the shoe to be made, the side nippers 2, 2' are rockable in the direction of the converging sides of the shoe toe and, in addition, laterally adjustable to different distances with respect to the longitudinal axis of the shoe, whilst the ball nippers can be adjusted both in the longitudinal and in the transverse direction to the shoe axis. In the arrangement according to the invention the adjustment of the nippers is rendered very easy compared with the known machines of this kind, since the nippers themselves can be of very light construction, owing to the simple hydraulic drive.

The tubular extension 28 forms the guide for a sleeve 30, to the upper end of which the immovable nipper jaw 31 of the stretching nippers and a pin 32 is fixed, about which the rockable nipper jaw 33 turns. The sleeve 30 is connected by means of a hollow rod 34 which extends through a stuffing box 35 of the nut 36 shutting

off the upper part of the working cylinder 27, with the hollow piston 37 which has the special form shown in Figures 2 and 3. The transverse partition 38 of the piston 37 is provided with a series of apertures 39 which connect the space 40 in the hollow part of the piston with the space 41 above the piston. On the outside of the transverse partition 38 there is provided a seating for the valve 42 which is displaceable on the threaded part 43 of the piston 37. This valve 42 is pressed against the seating in the transverse partition 38 by a spring 44 which bears against a collar 45 screwed on to the upper end of the threaded part 43. The casing of the piston 37 is also provided with a number of inlet openings 46.

In the hollow rod 34 a rod 47 is guided, to the lower end of which a piston 48 is fixed, which is guided on the inner surface of the piston 37. This piston 48 is provided at both sides with 20 packing rings 49 and at the inner side with a distance sleeve 51 (Figure 3) with apertures 50. The upper part of the rod 47 has a tubular extension 52 (Figure 2), the forked end 53 of which is provided with grooves 54, in which a pin 55 is slidable, which also co-acts with the guiding slot 56 of the rocking nipper jaw 33 which rocks about the pin 32.

On the rod 47 is also fixed a sleeve 57 which has at both ends inclined surfaces 58 which act against rounded ends 59 of two securing levers 60, which latter are mounted so as to rock on pins 61 in slots 62 of the sleeve 30. The manner, in which these securing levers operate, will be explained hereinafter.

In the fixed tubular extension 28 is a slot 64, in which a pin 65 slides, which is fixed in the sleeve 30. In the case of the toe and side nippers this guiding slot 64 is in a straight line, so that the sleeve 30 and with it the nipper jaws 31, 33 always retain the same axial position during the movement of the sleeve 30 in the tubular extension 28. In the case of the ball nippers, however, the slot 64 is curved in the upper part, with the result that, during the movement of the sleeve 30 in the tubular extension 28, an axial turning motion of the sleeve 30 together with the nippers takes place, which corresponds to the curvature of the slot 64.

The working cylinder 27 has three connections for the pressure fluid, namely at the place 66 which opens into the space 41 above the piston 37, a connection 67 opening into the space 40, that is into the space between the pistons 37 and 48, and finally a connection 68 which opens into the space 69 below the two pistons 37 and 48. The end of the working cylinder 27 is closed by a nut 154, the part of which lying within the working cylinder is provided with a reduced portion 155 which extends to about half way across the inlet opening 68. The upper edge of the reduced portion 155 is provided with grooves 156 which allow the pressure fluid to flow through out of the connection 68 under the piston 37, when the latter is in its lowest position, in which it comes up against the reduced portion 155.

The control of the flow of the pressure fluid into the working cylinders 27 of the individual nippers is effected by separate control slide valves, of which one is seen in detail by way of example in Figure 4. The casing 70 of the slide valve is mounted in the machine frame, namely in the lower part of the machine (cf. Figure 1) and is provided with three chambers 71, 72, 73. The chambers 71, 72 are control chambers and

the chamber 73 a reduction chamber. In the chamber 71 acts a piston 74, in the chamber 72 a piston 75 and in the chamber 73 a piston 76. The chambers 71 and 72 are exactly alike, as are also the pistons 74 and 75 associated therewith. The chamber 71 is connected by the inlet 77 with the pressure pipe 12 (according to Figure 1) and is provided on the one hand with an outflow 78 leading to the container 6 and on the other hand with through flow openings 79 and 80. The same functions are performed in the case of the chamber 72 by the inflow 81, the outflow 82 and the discharge openings 83, 84. The through flow opening 80 is in communication with the reduction chamber 73 and the latter through the opening 86 with the discharge 78. The piston 74 is provided with three recesses 87, 88, 89, of which the recesses 87 and 89 are connected with one another through the intermediary of the openings 90, 91 and the bore 92, which opens out of the left-hand end of the piston 74 into the outflow part of the chamber 71. The orifice of the bore 92 is closed by a valve 93 which is slidable on a rod 94 fixed in the bore 92 by the pin 95. The valve 93 is pressed by a spring 96 against its seating, which spring bears against a collar 97 fixed to the end of the rod 94. The valve 93 is under only slight spring pressure and has the object of permanently maintaining a pressure fluid column within the spaces connected with one another by the recesses 87 and 89, that is, in the discharge ducts 79 and 80 and in the working cylinder, in order that the working arrangement 35 can be put in operation immediately at any moment. This also prevents the formation of air bubbles and saves the unnecessary conveyance of pressure fluid. The piston 74 is permanently under the pressure of a spring 98 which seeks 40 to hold the piston in the position shown in Figure 4. At the right-hand end of the piston a roller 99 is mounted, which under the action of the spring 98 follows the track of a drive cam 149 (Figure 1). In the body of the piston 74 45 is fixed a pin 100 which projects out of both sides of the piston body and, in a middle position of the piston 74 engages in a recess 101 of a lever 102 which is adapted to rock freely about a pin 103 fixed in the valve casing. After 50 the pin 100 has engaged in the recess 101 the piston 74 is held in it, as long as the lever 102 is not raised. This raising may be effected either by means of a lever 104 which is adapted to be controlled by the worker in a manner to be described hereinafter and acts on a lateral arm 105 or by means of a cam acting on the 55 rounded end 106 of the lever 102.

The piston 75 operating in the chamber 72 is constructed like the piston 74 and its parts, 60 therefore, bear the same reference numerals as those of the piston 74, in so far as they are mentioned. Only the roller 107, the pin 108, the recess 109, the lever 110, the lever 111, the arm 112 and the rounded end 113 have new reference 65 numerals.

The two pistons 74, 75 have altogether three operative positions, of which the right-hand extreme position is seen in Figure 4, the middle position in Figure 5 and the left-hand extreme position in Figure 6.

The reduction of the pressure destined for the nipper pull is provided by the piston 76 in the chamber 73 which is in communication with the 70 through flow opening 80. The piston 76 is sub-

ject to the pressure of a spring 114, the pressure of which can be regulated by means of a small hand wheel 115 (cf. Figure 1) over the bevel wheels 116 and a nut 118 on the screw 117, against which nut one end of the spring 114 bears. The displacement of the piston 76 to the right (see Figure 4) is limited by a pin 119. The pressure in the conduit behind the reduction valve is checked by a pressure gauge 120 (Figure 1) which is connected to the bore 121 opening into the through flow opening 80 (Figure 4).

For each group of nippers there is a control slide valve. For the toe nipper 1 is provided the control valve 122 (Figure 1), for the side nippers 2, 2' the valve 123 and for the ball nippers 3, 3' the valve 124. The connection of the individual controlling valves to the groups of nippers is shown in Figure 1 and is preferably by way of flexible tubes. In those cases, where a single valve controls several nippers, a distributor of a known kind is used, which enables the pressure fluid to be distributed from a single outlet to the valve at various operative places. All the groups of nippers are connected to the individual valves in substantially the same manner. It should therefore be sufficient to describe only one of these connections in detail, for instance that of the side nippers 2, 2' to the valve 123.

The outlet opening 79 (Figure 4) is connected by means of a flexible tube 125 (Figure 1) directly with the supply point 68 (Figure 2) of the working cylinder of the nippers 2 and the discharge opening 84 by means of a flexible tube 126 directly with the supply point of the nippers 2'. From the discharge opening 80, where reduced pressure prevails, the pressure fluid is conveyed by means of a tube 127 into a distributor 128 of known design and from there through tubes 129 and 130 to the supply points 67 of the nipper 2 and 2', respectively. In the same way the pressure fluid is conveyed from the opening 83 through the tube 131 into the distributor 122 and from there through the tube 133 into the supply point 66 of the nipper 2 and the tube 134 into the supply point 66 of the nipper 2'. In the case of the toe nipper 1 a distributor is not necessary; the discharge opening 80 of the valve 122 can, therefore, be connected directly with the supply point 67 of the nipper 1. The pull of the nipper 1 is checked by a pressure gauge 135 and the pull of ball nippers 3, 3' by a pressure gauge 136.

The control of the valves is effected in two different ways, on the one hand by the worker by means of a system of levers and on the other hand automatically by means of cam discs. In Figure 1 the lever control for the valve 123 of the side nippers 2, 2' is illustrated diagrammatically. This lever control consists of a knee-actuated lever 137 which is capable of rocking laterally about a pivot pin 138. This knee lever 137 is connected by means of a pull rod 139 to a lever arm 140 keyed on a shaft 141. The shaft 141 is rotatable in suitable bearings and supports several other keyed-on lever arms, namely the lever arm 142, which acts on the pin 25 (see Figure 7) of the piston 21 of the idle running valve 10, and a further forked lever 143, of which one arm 144 acts on the lower part of the pin 100 (see Figure 4) and the other arm 145 on the pin 103, when the shaft 141 is turned in the counter-clockwise direction. The arm 145 is turned somewhat to the left with respect to the arm 145, namely by half the length of the stroke of the pistons 74 and 75, which will be described

in detail hereinafter. On the shaft 141 there is also keyed a forked lever 146, the arms 104 and 111 of which have already been referred to, which arms act on the pins 105 and 112 (Figure 4), when the shaft 141 is turned in the clockwise direction. The valve 122 is controlled in the same manner, the arrangement being such that the two valves can be controlled by means of a single knee lever 137, movements of the same forwards and backwards being combined. The ball nippers 3, 3' and correspondingly the associated valve 124 are, for reasons explained below, controlled only automatically, namely by cam discs.

For reasons explained hereinafter the piston 21 (Figure 7) of the idle running valve must be displaced to the left, even when the control lever 137 is displaced to the right. This action is brought about, for instance, by an arrangement indicated in Figure 8, in which the lever 142, when swinging to the right, forces by means of a push rod 157 and a beam 158 which is pivoted on a pin 159 fixed in the machine frame the pin 25 of the piston 21 to the left.

The automatic drive, if desired, of the control valves is effected by means of cam discs on the shaft 47, which is driven by way of a gear box 148 and a single revolution coupling (not shown) from the motor 5. With each control valve are associated two cams, namely, with the valve 123 the cams 149 and 150. The idle running valve 10 is controlled by a single cam 151.

The described arrangement operates in the following manner:

By starting the electric motor 5 the pump 4 is put in operation, which draws the pressure fluid by suction through a filter 8 out of the container 6 and conveys it through a pipe 9 to the idle running valve 10. As long as the machine itself is still inoperative, the pump 4 runs without load, as the pressure fluid can return without performing pressure work out of the pump by way of the idle running valve 10 back to the container 6. The piston 21 of the idle running valve 10 at the same time occupies its right hand extreme position, that is to say a position which is derived from Figure 7 through the displacement of the piston 21 to the right by the whole length of the recess 23. The pressure fluid can in this position flow out of the pipe 9 through the recess 19 around the conical extension 22 of the piston and between the ribs 23 into the discharge pipe 18.

The worker then takes up the work and places it in the machine, proceeding in substantially the same manner as with the majority of machines of this kind. He first of all inserts the marginal portion of the upper at the toe of the shoe between the jaws of the nipper 1, which are in their highest position and are open, as are all the other nippers. By swinging aside the knee lever 137 (Figure 1) he causes by means of the control valve 122 the closing of the toe nipper which clamps the upper, so that he is enabled to stretch it tightly in a suitable manner in the longitudinal axis of the last. He thereupon inserts the marginal portions at the side of the upper into the side nippers 2, 2' and, after forcing down the last against a support of a known kind (not shown), he closes the jaws of the nippers 2, 2' as well by swinging the knee lever 137 to the left, so that the upper can be tightly stretched at the sides as well. The upper is only gripped by the ball nippers and stretched tightly in the ball part of the last, when the worker has made sure that the upper has been correctly pulled over both at the toe and at the sides. As the ball nippers can

no longer substantially influence the correct stretching over of the upper gripped and held by the toe and side nippers, it is not necessary for the ball nippers to be controlled by the worker himself, so that in the constructional example illustrated this is effected only automatically from the cam shaft 147.

Before the commencement of the operation, as already stated, all the nippers are open and the toe nipper 1 as well as the side nippers 2, 2' are in their uppermost position. The ball nippers 3, 3' may be positioned somewhat lower, so that they will not be in the way, when the marginal portion of the upper is being inserted in the other nippers, and only, when the upper is to be inserted in the ball nippers, are the latter raised. Before the commencement of the operation the actuating device of each of the nippers occupies the position shown in Figure 2, whilst the two pistons 74, 75 of the associated control valve according to Figure 4 are still, from the previous operation, under the pressure of the space 69 of the working cylinder 27 (Figure 2) of the nippers, as they are in communication through the tubes 125, 126, the discharge openings 79, 84, the recesses 88 and the inlets 77, 81 with the pressure pipe 12 (Figure 1). Both pistons 37 and 48 of the nippers are in their uppermost positions, since both spaces 40 and 41 (Figure 2) are without pressure, as they are in communication by way of the associated conduits with the discharge openings 80 and 83 which are connected by way of the recess 87, the opening 90, the bore 92 and the valve 93 with the discharge pipes 18 and 82.

As soon as the worker has inserted the marginal portion of the upper between the opened jaws 31, 33 of the nippers, he causes by swinging the knee lever 137 (Figure 1) to the left the gripping and stretching of the upper part until the nippers come to rest in the tensioning motion. Through the lever 137 being swung to the left the shaft 141 is caused to rotate and the levers 142, 143 and 146 fixed on it are also caused to swing to the left. During this swinging motion, however, only the levers 142, 143 come into operation, the action of which corresponding to their inclination is so distributed in respect to time that the lever 142 comes into action on the pin 25 of the piston 21 of the idle running valve at the same time as the arm 144 of the lever 143 comes into action on the lower part of the pin 109 of the piston 74 of the control valve, whilst the arm 145 of the lever 143 only comes into action later on the pin 108 of the piston 75, the retardation with respect to the longitudinal dimensions amounting to half the stroke of the piston 74. The lever 142 pushes the piston 21 of the idle running valve into the left hand extreme position shown in Figure 7, in which the discharge of the pressure fluid into the discharge pipe 18 is shut off and the way into the pressure pipe 12 is laid open, the pressure fluid opening the non-return valve 152 itself. The piston 74 of the control valve moves under the action of the arm 144 of the forked-lever 143 into its left hand extreme position according to Figure 6, whilst the piston 75 under the influence of the arm 145 occupies a middle position according to Figure 5. The result of this is, that the pressure fluid passes out of the pressure pipe 12 through the inlet 77 and the recess 88 into the discharge opening 80, to which the reduction chamber 73 is connected, in which the pressure is reduced as required, corresponding to the adjustment of the spring 114 by the hand wheel 115, any superfluous pressure fluid forcing the piston 76 back and escaping through

the opening 86 into the discharge 78 (Figure 4). The pressure fluid passes with reduced pressure through the discharge opening 80 and the associated conduits into the inflow opening 67, that is 5 into the space 40 according to Figure 2. At the same time the pressure fluid escapes from the space 69, which was hitherto under pressure through the associated conduits into the openings 79 and 84 and from the latter only through the opening 84 by the communicating bore 85, into the recess 89 of the piston 74 and from there through the opening 91, the bore 92 and by way of the valve 93 into the discharge 78. In this working phase 10 the pressure fluid cannot pass directly through the opening 84 into the discharge pipe 82, as long as the piston 75 occupies the said middle position according to Figure 5, in which both the inflow 81 and the discharge openings 83 and 84 are closed. 15 As has already been stated, the pressure fluid has the possibility of passing out of the opening 84 through the communicating bore 85 into the discharge, during which the spaces connected with the discharge opening 80 lose the pressure. 20 It is true, but remain filled with pressure fluid, which is brought about by the spring-loaded valve 93. It follows, that, as soon as pressure fluid reaches the space 40 of the working cylinders of the nippers, there will in the first instance be 25 a displacement of the piston 48 downwards (according to Figure 2 obliquely downwards to the right), so that the piston 48 will occupy the position shown in the upper half of Figure 3. At the same time the piston 48 will carry along with it 30 the rod 47 with the forked tubular extension 52 and the pin 55 which slides in the slot 56 of the movable nipper jaw 33 and turns the latter about the pin 32 in such a manner that the said jaw is caused to bear against the fixed nipper jaw 31, 35 thereby clamping the marginal portion of the upper. The closing of the nipper jaws prevents the possibility of any further displacement of the rod 47 and the piston 48 downwards, the pressure in the space 40 begins to rise, until it exceeds the 40 force of the spring loading the valve 42, opens this valve and causes pressure fluid to begin to flow through the openings 39 in the transverse partition 38 into the space 41, as can be seen from the lower half of Figure 3. As long as the inflow opening 66 in the space 41 remains blocked by the piston 75 of the control valve, as stated above, the pressure in the space 41 will act on the entire 45 surface of the hollow piston 48 and commence to force this piston 48 together with the piston 37 further downwards (according to Figure 3 to the right), until both pistons reach the position 50 shown in the lower part of Figure 3. During this combined displacement of the pistons 37 and 48 the tubular extension 28 together with the nipper 55 jaws 31, 33, between which is the clamped marginal portion of the upper, is also carried along and the upper is stretched over the last. The 60 pressure in the now connected spaces 40 and 41 rises in proportion to the resistance offered by the upper to being tensioned, causing not only the pull of the nippers to increase, but also the gripping force of the nipper jaws 31 and 33 against one another. The pressure in the spaces 65 40, 41 continues to rise, until it reaches its maximum value determined by the reduction piston 76, whereupon the further pulling motion of the nipper ceases.

When the worker desires to reach the maximum pull of the nippers as quickly as possible, he holds the knee lever 137 in its left hand posi-

tion, until the pulling motion of the nipper ceases. As soon as the worker releases the knee lever 137, it will return automatically under the action of the spring 24 of the idle running valve 10 into the initial position, when the piston 21 will also be displaced into the right hand extreme position, the pin 25 of the piston 21 carrying the lever 142 of the shaft 141 along with it. The worker will, however, not always utilize the full reduced nipper pull, but, should a weak upper part make this necessary, will allow the pull to increase step by step, by alternately displacing the knee lever 137 to the left and releasing it again and thereby interrupting and restarting the pulling motion of the nippers which he can repeat over and over again, until the upper is correctly stretched over the last.

As has been just explained, the knee lever 137 returns each time it is released automatically into the initial position and the control piston 21 of the idle running valve 10 occupies its right hand extreme position, in which the inflow of the pressure fluid into the pressure pipe 12 is blocked. Owing to the fact that the knee lever 137 returns into the initial position, the forked lever 143 also moves away from the pistons 74 and 75 of the control valve and these two pistons seek under the action of the springs 98 also to return into their initial position, that is, into the right hand extreme position. This is, however, prevented by the levers 102, 110, in the recesses 101 and 109 of which the projecting pins 100 and 108 have already engaged. The recesses 101 and 109 thus hold both pistons 74 and 75 in the middle positions according to Figure 5, in which both the inflow and the outflow openings of the control valve are closed. Through the release of the knee lever 137, which has been swung aside, a blocking of the entire working arrangement of the nippers is thus brought about in the position in which the nippers happened to be at the moment of release of the knee lever. Each time the knee lever 137 is again swung to the left, only the piston 74 is displaced to the left in the control valve, until it reaches, say the left-hand extreme position again (the piston 75 remains in its middle position, in which it had already been set after the first swinging aside of the knee lever) and a renewed action of the pressure fluid takes place in the spaces 40 and 41 of the working cylinder of the nipper, so that the increase in pressure in these spaces progresses up to the eventual maximum value.

In the case of an incorrect gripping and stretching of the upper over the last it is possible to release the upper again from the nippers and to set the whole arrangement back into the initial position, by swinging the knee lever 137 in the opposite direction, that is to the right, when the arms 104 and 111 of the forked lever 143 will strike against the pins 105, 112 of the levers 102, 110 and raise them, whereby the pins 100 and 108 are brought out of engagement with the recesses 101, 109 of these levers and the pistons 74, 75 of the control valve return under the influence of the springs 98 into their right hand extreme position shown in Figure 4, in which both spaces 40 and 41 of the nippers are connected to the discharge. As, however, on the knee lever 137 swinging to the right as well, the idle running arrangement is blocked, that is to say, the piston 21 of the idle running valve 10 is forced into the left hand extreme position according to Figure 7, in which the inflow of the pressure fluid into the pressure pipe 12 is set free,

the fluid will flow through the supply conduits 77 and 81 by way of the recesses 88 of the pistons 74, 75 and through the openings 79, 84 and the associated flexible tubes into the spaces 69 of the working cylinders 27 of the nippers, so that the two pistons 37 and 48 of the latter will return into their upper position shown in Figure 2, the nippers opening and moving upwards.

In addition it is also possible to correct the position of the upper which has already been gripped by the nippers and put under tension by them by adjusting individual nippers in their closed state with respect to the shoe support, which may be effected by means of a system of levers of a known kind (not shown), which act on the outer socket 29 of the working cylinders of the nippers.

The case may also occur, in which the upper is incorrectly placed between the still open nipper jaws and, although the latter close, they do not grip the upper and perform the pulling motion, while empty. Since in this case the motion of the nippers encounters no resistance, it might occur that both pistons 37 and 48 will move downwards until they strike against the reduced portion 155 of the closing nut 154 of the working cylinder 27. The same thing might occur if the nippers, although correctly gripping the upper, should tear it away when tensioning it. For this reason the rod 47 is provided with the sleeve 57 with bevelled end surfaces which, on the nipper jaws 31, 33 closing, mount the rounded ends 59 of the safety levers 60, causing the latter to move apart. A downward movement of the nippers to the aforesaid stop is thereby prevented, as the ends of the safety levers 60, through projecting out of the sleeve 30, strike against the end surface 63 of the tubular extension 23 and thereby render a further downward movement of the nippers into the undesired position impossible.

The ball nippers 3, 3' which during the whole of the time occupied by the preparation of the upper, while being inserted into the nippers 1, 2 and 2', are released and are brought into the uppermost position according to Figure 2 through the admission of pressure fluid into the space 69.

With the stretching of the upper over the last by the point and side nippers the first phase of the operation of the machine is finished. The second phase is now initiated, which is characterised by the automatic running of the machine.

The marginal portion of the upper is inserted between the opened jaws of the ball nippers 3, 3' and, through throwing in a coupling, the cam shaft 147 is put in rotation, the cams of which perform the function of controlling the work of the nippers during the further operation, by causing through the intermediary of the control valves the pressure fluid to flow out of the pressure pipe into the working cylinders. On the shaft 147 being started up, in the first place by means of the cam 151 acting on the roller 26 of the piston 21 the idle running motion is blocked and the pressure pipe thereby connected with the pump, the control valve 124 being at the same time put into operation by means of further cams, similarly as previously by means of the knee lever 137, such that the ball nippers 3, 3' are caused to close, to grip the marginal portion of the upper and, at the same time turning axially in the manner already described, to stretch the upper in the ball region of the shoe over the last. After these nippers have completed the pulling motion, the pistons 74 and 75

of the control valves of all the nippers will be in the middle positions according to Figure 5.

At this moment, that is to say, when the stretching operation of the upper on the last is finished, the further devices of the tacking machine are put into operation, for instance a toe form (not shown) of a known construction, which presses the upper at the toe against the last and thus secures it against displacement or loosening of the tension after its release from the nippers, which release must take place, in order that the pushing over members of a known kind (not shown) and finally the nailing or sticking and pressure applying device for finish tacking the upper can come into action. It is therefore not enough for the nippers merely to open and release the marginal portion of the upper, they must also move downwards some distance, in order that they shall not be in the way of the further working devices referred to.

The opening of the nipper jaws and the consequent release of the upper is effected by the cams 149 and 150 which in the first place by acting on the rounded ends 106 and 113 of the levers 102, 110 raise the latter and bring the pins 109 and 108 out of engagement with the recesses 101, 109. The cam 149 enables the piston 74 under the influence of the springs 98 to return into the right hand extreme position (cf. Figure 4), whilst the cam 150 leaves the piston 75 in the middle position (cf. Figure 5). In these positions of the pistons 74, 75 the spaces 40 of the working cylinders of the nippers are in communication through the inlet openings 46 (Figure 3) with the supply conduits 61 and by way of the associated flexible tubes with the discharge conduits 80 of the control valves and these openings in addition by way of the recesses 87, the openings 90, the bores 92 and the valves 93 with the discharge. The result of this is that the pressure in the space 40 drops, whilst the pressure in the space 41 still remains constant, since before the pressure equilisation in the spaces 40, 41 have been brought about, the non-return valve 42 under the action of the spring 44 has blocked the connection between the spaces 40 and 41. At the same time as the spaces 40 are connected to the discharge opening the spaces 69 are connected to the inlet for the pressure fluid, namely in the manner already described, so that through the pressure arising in the spaces 69 the pistons 48 are displaced with respect to the pistons 37 upwards (according to Figure 3 to the left). During motion of the piston 48 the pin 55 of the rod 47 moves in the slot 56 of the nipper jaw 33 forwards and swings the latter into the open position shown in Figure 2, thus causing the upper to be released from the nippers. The piston 37 of the nippers can for the time being not yet move upwards, as pressure is still present in the space 41 above this piston. During the motion of the piston 48 upwards with respect to the piston 37 the safety levers 60 re-occupy their original position according to Figure 2, that is to say, they fall back into the grooves 62 and nothing more stands in the way of the eventual pushing back of the sleeve 30 together with the nippers, now open, downwards, so that the piston 37 can move downwards until it strikes against the reduced part 155 of the closing nut 154 at the bottom of the working cylinder 27.

After the release of the upper by the nippers, it is necessary for the latter to be immediately displaced somewhat downwards, in order that 75 means including a hydraulic working cylinder,

they shall not be in the way of the pushing over members and the fixing devices for the marginal portions of the upper. The downward movement of the opened nippers is produced by the cams 149 and 150, through the piston 74 being forced into the middle position (Figure 5) and the piston 75 into the left hand extreme position (Figure 6). The result of this is, that the opening 80 connected with the spaces 40 and the opening 65 of the distributor valve is closed, whilst pressure fluid passes through the inlet 81 into the chamber 72 of the piston 75 and flows through the recess 88 of the piston 75 to the discharge opening 83 and thence through the associated flexible tubes into the spaces 41 above the piston 37. From the spaces 69 below the piston the pressure fluid flows down into the discharge, as these spaces 69 are in communication through corresponding conduits with the opening 84, the bore 85, by way of the recess 89, the openings 91, the bore 92 and through the valve 93 of the piston 75 with the discharge pipe 82. Consequently, the pressure fluid in the space 41 forces both pistons 37, 48 downwards (that is, according to Figure 3 to the right), until the downward movement of the nippers is brought to an end through the piston 37 coming against the reduced part 155 of the closing nut 154 at the bottom of the working cylinder 27.

After all the operations of the tacking machine have come to an end, the cams 149 and 150 finally cause the return of the opened nippers into the original position through the two pistons 74, 75 of the control valve allowing the return into the right hand extreme position according to Figure 4, in which the spaces 40, 41 are connected to the discharge, whilst the pressure fluid flows in the manner already described through the slots 156 in the reduced portion 155 of the closing nut 154 at the bottom of the working cylinder 27 into the space 69 below both pistons 37, 48 and displaces these two pistons into the initial position shown in Figure 2.

After the return of the nippers into the initial positions the work of the machine is finished and a special coupling, after the cam shaft 141 has performed one revolution, automatically disconnects the drive of the latter.

We claim:

1. A shoe making machine comprising a system of stretching nippers for stretching the upper part of shoes over a last, means for alternately opening and closing the stretching nippers including an hydraulic cylinder with opposed differential pistons therein connected to the stretching nippers for opening and closing the latter to perform pulling and return motions, a spring loaded bypass valve associated with one of said pistons and controlling the flow of fluid from a chamber between the pistons, the differential pistons cooperating in such a manner that during the stretching motion of the nippers the tractive force of the nipper jaws increases in the ratio of the increasing resistance of the upper to a definite maximum value, the closing force of the nipper jaws increasing at the same time to a corresponding extent.

2. A shoe-making machine comprising: a system of stretching nippers for stretching the upper part of a shoe over a last, each nipper having a fixed jaw and a pivoted jaw, means for alternately opening and closing the stretching nippers and for causing the stretching nippers to perform pulling and return motions, said latter means including a hydraulic working cylinder,

a hollow piston slideable in the cylinder and supporting the fixed nipper jaw, and a piston slideably mounted within the hollow piston and connected with the pivoted nipper jaw, these hydraulic members co-operating in such a manner that during the stretching motion of the nippers the tractive force of the nippers increases in the ratio of the increasing resistance of the upper up to a definite maximum value, the closing force of the nipper jaws increasing at the same time to a corresponding extent.

3. A shoe-making machine comprising: a system of stretching nippers for stretching the upper part of a shoe over a last, each nipper having a fixed jaw and a pivoted jaw, means for alternately opening and closing the stretching nippers and for causing same to perform pulling and return motions, said latter means including a hydraulic working cylinder, a hollow piston slideable in the cylinder and supporting the fixed nipper jaw, a piston slideably mounted within hollow piston and connected with the pivoted nipper jaw, a transverse partition in the hollow piston, and a by-pass valve provided in the said partition, connecting a space above the hollow piston with the space between the two working pistons, these hydraulic members co-operating in such a manner that during the stretching motion of the nippers the tractive force of the nippers increases in the ratio of the increasing resistance of the upper up to a definite maximum value, the closing force of the nipper jaws increasing at the same time to a corresponding extent.

4. A shoe-making machine, comprising: a system of stretching nippers for stretching the upper part of a shoe over a last, each nipper having a fixed jaw and a pivoted jaw, means for alternately opening and closing the stretching nippers, and for causing same to perform pulling and return motions, said latter means including a hydraulic working cylinder, a hollow piston slideable in the cylinder and supporting the fixed nipper jaw, a piston slideably mounted within the hollow piston and connected with the pivoted nipper jaw, the working cylinder being formed with three openings for the admission of pressure fluid, one of which admits it above the hollow piston, one between the two working pistons, and one below the pistons.

5. A shoe-making machine, comprising: a system of stretching nippers for stretching the upper part of a shoe over a last, each nipper having a fixed jaw and a pivoted jaw, means for alternately opening and closing the stretching nippers and for causing the stretching nippers to perform pulling and return motions, said latter means including a hydraulic working cylinder, a hollow piston slideable in the cylinder and supporting the fixed nipper jaw, a piston slideably mounted within the hollow piston and connected with the pivoted nipper jaw, the opening and closing of the nipper jaws being effected by a relative displacement of the two pistons that are guided one within the other, caused by pressure fluid being admitted into or discharged from the space between the two pistons, these hydraulic members co-operating in such a manner that during the stretching motion of the nippers the tractive force of the nippers increases in the ratio of the increasing resistance of the upper up to a definite maximum value, the closing force of the nipper jaws increasing at the same time to a corresponding extent.

6. A shoe-making machine comprising: a system of stretching nippers for stretching the upper part of a shoe over a last, means for alternately opening and closing the stretching nippers and for causing the stretching nippers to perform pulling and return motions, said latter means including a hydraulic working cylinder, a hollow piston slideable in the cylinder and supporting one nipper jaw, a piston slideably mounted within hollow piston and connected with the other nipper jaw, a spring-loaded by-pass valve connecting a space above the hollow piston with the space between the two working pistons, so that upon pressure fluid being admitted into the space between the two working pistons the pressure in this space, which rises after the closing of the nipper jaws, opens the by-pass valve, enters the space above the hollow piston, and from there acts on both working pistons simultaneously, thereby forcing both pistons downwards and exerting a tensile stress on the work.

7. A shoe-making machine comprising: a system of stretching nippers for stretching the upper part of a shoe over a last, means for alternately opening and closing the stretching nippers and for causing the stretching nippers to perform pulling and return motions, said latter means including a hydraulic working cylinder, a hollow piston slideable in the cylinder and supporting one nipper jaw, a piston slideably mounted within the hollow piston and connected with the other nipper jaw, the opening and closing of the nipper jaws being effected by a relative displacement of the two pistons that are guided one within the other, caused by pressure fluid being admitted into or discharged from the space between the two pistons, and a spring-loaded by-pass valve connecting a space above the hollow piston with the space between the two working pistons, these hydraulic members co-operating in such a manner that the closing force of the nipper jaws before the initiation of the tensioning motion of the nippers is dependent upon the spring loading of the by-pass valve, whereas during the stretching motion of the nippers the tractive force of the nippers increases in the ratio of the increasing resistance of the upper up to a definite maximum value, the closing force of the nipper jaws increasing at the same time to a corresponding extent.

8. In a shoe-making machine as claimed in claim 1, two working chambers and pistons therein constituting a single slide valve for controlling several nippers which operate in the same manner as regards the motion and time phases, a system of manually operated levers for actuating the pistons, and cams whereby the machine operates the pistons automatically.

9. In a shoe-making machine as claimed in claim 1, two working chambers and pistons therein constituting a single slide valve for controlling several nippers which operate in the same manner as regards the motion and time phases, and a control lever for so adjusting the pistons of the slide valve as to effect the closing and the pulling motion of the said nippers by admitting pressure fluid into the space between the differential pistons of the hydraulic cylinder and opening a space beyond these pistons to exhaust, the arrangement being such that the operation of the nippers can be interrupted by means of the control lever at any desired moment and the nippers fixed in their momentary position or returned immediately into their initial position.

10. In a shoe-making machine as claimed in

claim 1, two working chambers and pistons therein constituting a single slide valve for controlling several nippers which operate in the same manner as regards the motion and time phases, a control lever for so adjusting the pistons of the slide valve as to effect the closing and the pulling motion of the said nippers by admitting pressure fluid into the space between the differential pistons of the hydraulic drive and opening a space below these pistons to exhaust, and safety elements for holding both pistons of the slide valve in positions in which pressure fluid does not flow either into or out of the hydraulic driving means of the nippers, the arrangement being such that the operation of the nippers can be interrupted by means of the control lever at any desired moment and the nippers fixed in their momentary position or returned immediately into their initial position.

11. In a shoe-making machine as claimed in claim 1, two working chambers and pistons therein constituting a single slide valve for controlling several nippers which operate in the same manner as regards the motion and time phases, a control lever for so adjusting the pistons of the slide valve as to effect the closing and the pulling motion of the said nippers by admitting pressure fluid into the space between the differential pistons of the hydraulic drive and opening a space below these pistons to exhaust, safety elements for holding both pistons of the slide valve in positions in which pressure fluid does not flow either into or out of the hydraulic driving means of the nippers, springs for returning the pistons of the slide valve into their initial positions after the release of the safety elements, and thereby putting a space above the differential pistons of the nippers and also the space between

these differential pistons into communication with the exhaust and at the same time opening the space below these differential pistons to pressure fluid, thus forcing these differential pistons upwards, re-opening the nipper jaws and returning the nippers to their initial positions.

12. In a shoe-making machine as claimed in claim 1 and in which additional side nippers are provided for applying the upper, two working chambers and pistons therein constituting a single slide valve for controlling several nippers which operate in the same manner as regards the motion and time phases, a system of manually operated levers for actuating the pistons of the slide valve, and cams that come into operation automatically when the actual operation of stretching the upper over the last by means of the nippers is finished, these cams then effecting the opening of the nipper jaws to release the marginal portion of the upper, the evasive motions of the nippers downwards, and the return of the open nippers into the initial position.

JOSEF ZAORAL.
